UNITED STATES PATENT OFFICE

PETER MARCZYNSKI, OF MILWAUKEE, WISCONSIN

PROPELLER

Application filed October 22, 1927. Serial No. 227,996.

My invention refers to propellers, the same being equally adaptable to marine and air propulsion.

The object of my invention is to increase the efficiency of the standard propeller, and with this in view, provision is made for increasing the area of the propeller blades by the application thereto of multiple auxiliary vanes.

10 With the above object in view the invention consists in certain peculiarities of construction and combination of parts as are to be hereinafter set forth with reference to the accompanying drawing.

15 The drawing illustrates a face view of the propeller, embodying the features of my invention.

Referring by characters to the drawing, 1 represents any type of standard hub having 20 extended therefrom standard radial blades 2—2. It is understood that these blades may be varied to meet the requirements and in accordance with well-known principles of standard propeller construction.

25 Secured to the ends of the blades 2 in this exemplification of my invention, are pairs of auxiliary vanes 3—3, which vanes are spaced from the main propeller blade in each instance, and are rigidly secured thereto by 30 posts 4 and 5, it being preferable to provide a single intermediate post and a pair of outer posts forming a triangular tying connection to the main blade.

Obviously the auxiliary blades may be varied in number to meet certain requirements, and the shapes of said auxiliary vanes preferably coincide with the shape of the ends of the standard blade.

40 It is obvious from the foregoing description that the great increase in area at the ends of the blades will materially increase the pulling or pushing power of the propeller, and that said propeller so arranged can be rotated at a slower speed and at the same time greater efficiency is maintained. Furthermore, the danger of accidents, due to breakage of propellers upon aeroplanes, is eliminated for the reason that the auxiliary blades serve as 45 guards or shields for the main blade, which

main blade, in the event of damage to the auxiliary vanes, would still function.

While I have shown and described one simple exemplification of my invention as illustrated and described, it is understood that 55 I may vary the structural features within the scope of the claim.

I claim:

A propeller comprising a pair of main vanes having enlarged rounded outer ends, 60 a pair of auxiliary vanes associated with each of said main vanes and of the same size and shape and located adjacent the outer ends and on opposite sides of the main vanes, said auxiliary vanes being of oval shape with 65 their larger ends outermost and rigidly secured to said main vanes by a pair of laterally spaced posts at their outer and larger ends and an inner post at their inner and smaller ends.

70 In testimony that I claim the foregoing I have hereunto set my hand at Milwaukee, in the county of Milwaukee, and State of Wisconsin.
